UNITED STATES PATENT OFFICE.

ALBERT HAMILTON EMERY, OF STAMFORD, CONNECTICUT, ASSIGNOR TO
THE EMERY SCALE COMPANY, OF SAME PLACE.

HOLDER FOR TESTING-MACHINES.

SPECIFICATION forming part of Letters Patent No. 308,957, dated December 9, 1884.

Application filed February 7, 1884. (No model.)

To all whom it may concern:

Be it known that I, ALBERT HAMILTON EMERY, a citizen of the United States, formerly of New York, now residing at Stamford, 5 in the county of Fairfield and State of Connecticut, have invented certain new and useful Improvements in Holders for Testing - Machines, of which the following is a specification.

10 This invention relates to a holder for testing-machines constructed with paired wedges sliding within converging seats in a sleeve or casing, so that the strain applied to the specimen will cause the wedges to grip it firmly.

15 The simultaneous and equal movement of the wedges longitudinally is compelled by connecting them together without interfering with their radial movement to and from each other. The converging seats of the wedges

20 are formed in a bushing screwed within the sleeve or casing of the holder and reversible with the wedges, so that the holder may be adapted for applying strains of either tension or compression and causing the gripping of

25 the specimen by the strain applied thereto.

The above-recited features are also described in another application of mine of even date herewith.

My present improvements consist in part in 30 constructing a holder with two or more paired wedges, so as to grip a specimen of cylindrical or other shape with a uniform pressure on all sides; also in constructing a reversible converging bushing in two or more parts doweled together; also in the employment of a fixing-plate engaging in recesses in the heels of the wedges to compel their uniform movement; also in the employment of bushings for reducing the aperture of the holder for conforming 35 to the size of the specimen, said bushings having shoulders and dowels engaging in recesses so as to secure them against slipping or movement relatively to the wedges.

In the accompanying drawings, Figure I is 40 a longitudinal section of the improved holder adapted to a specimen of cylindrical form. Fig. II is a front view of the same. Fig. III is an elevation showing three of the connected wedges and bushings adapted to grip a square 45 specimen, the fourth wedge being omitted to expose the improved holding-plate which se-

cures them against relative longitudinal movement. Fig. IV is a front or end view of the four wedges and bushings adapted to grip a specimen of square section.

55 The wedges 11 may be four, six, or more in number, and are arranged in pairs so as to grip a specimen at opposite points. They slide longitudinally in converging seats, and within a bushing, 5, secured within the sleeve 60 or casing of the holder, and reversible to fit the wedges, so as to adapt them to operate in applying strains of either tension or compression, and to tightly grip the specimen by the force of the strain applied. A ring or annular plate, 6, is inserted in the annular recess between the screw-thread and the face of the holder in order to adapt the sleeve to provide a solid bearing and support to sustain the radial pressure of the wedges under strain.

70 To compel the uniform and simultaneous movement of the wedges without interfering with their radial motion to and from each other, I employ a plate, 4, Figs. III and IV, occupying recesses 3 in the faces of the wedges 75 near their heels and secured to one of the wedges by a screw, 4^a. In my present invention this plate, which is removable with the combined set of wedges and is independent of the stem or shank 7 of the holder, takes the 80 place of the plate or head 9^a guided by a stem, 9, as shown in Fig. I, and described and claimed in another application of mine of even date herewith. One or more springs, 8, bearing through a plunger, 9, against the heels of the 85 wedges press them forward so as to apply initial pressure to the specimen.

To adapt the holder to the size of the specimen to be tested, I employ bushings 10 of suitable shape and thickness, having shoulders 11 90 and dowels 12 fitting in corresponding recesses in the faces of the wedges, so as to secure the bushings against longitudinal or lateral movement relatively to the wedges. In Figs. I and II two pair of wedges are shown with bushings 10 adapted to a specimen, 13, of cylindrical form.

In Figs. III and IV bushings 10 are shown adapted for operating on a square bar.

14 represents an ejecting-spring within the 100 stem of the holder operating on a plunger, 15, so as to throw the specimen out when it is re-

leased by the forcing back of the wedges, which is effected by any suitable device. The wedges are, furthermore, formed with splines 16, occupying corresponding grooves in the bushing 5, so as to withdraw them by an outward radial movement from the specimen when they are forced back longitudinally.

Having thus described my invention, the following is what I claim as new therein and desire to secure by Letters Patent:

1. A holder for testing-machines constructed with two or more pairs of wedges having cylindrical backs to permit them to rock on their axes and to slide longitudinally, and 15 adapted for gripping specimens of square, round, or other section on opposite sides.
2. The combination of gripping-wedges, a sleeve or case in which they slide, and a screw-bushing made in two or more parts doweled 20 together and forming seats for the gripping-wedges, substantially as set forth.
3. The combination, with the sleeve or case

and gripping-wedges, of a fixing-plate disconnected from the stem or plunger and fitting in recesses in the several wedges to compel 25 them to slide in unison, as set forth.

4. In combination with two or more sliding wedges, the shouldered inner bushings, fitting corresponding seats in the wedges, and serving to reduce the size of the opening. 30

5. In a holder for testing-machines, the combination, with the gripping-wedges and bushings, of dowel-pins for retaining the said bushings against movement relatively to the wedges, as explained. 35

6. In combination with the sleeve or case and gripping-wedges, the ejecting plunger and spring, substantially as and for the purpose set forth.

ALBERT H. EMERY.
